United States Patent Office

Des. 183,061
Patented June 17, 1958

183,061

TEXTILE FABRIC OR SIMILAR ARTICLE

Pierre Pizzella, New York, N. Y., assignor to Staron, Inc.,
New York, N. Y., a corporation of New York

Application March 14, 1958, Serial No. 50,030

Term of patent 3½ years

(Cl. D92—1)

The figure of the drawing is a plan view of a textile fabric showing my new design.

A unit is enclosed within the dot and dash lines on the drawing, which unit is repeated in regular succession as indicated by the extension beyond the unit boundaries.

I claim:

The ornamental design for textile fabric or similar article, as shown and described.
